CHESTER T. ALLCUTT, OF PITTSBURGH, PENNSYLVANIA, ASSIGNOR TO WESTINGHOUSE ELECTRIC & MANUFACTURING COMPANY, A CORPORATION OF PENNSYLVANIA.

DISCHARGE GAP.

Application filed April 4, 1919. Serial No. 287,573.

To all whom it may concern:

Be it known that I, CHESTER T. ALLCUTT, a citizen of the United States, and a resident of Pittsburgh, in the county of Allegheny and State of Pennsylvania, have invented a new and useful Improvement in Discharge Gaps, of which the following is a specification.

My invention relates to discharge gaps, as used in lightning arresters, and it has for its object to provide apparatus of the character designated that shall have a low impulse ratio, that is to say, the ratio of the potential at which the gap breaks down with high-frequency discharges to the potential at which the gap breaks down at normal frequency is low in value, preferably being considerably less than unity.

In the accompanying drawing, Fig. 1 is a diagrammatic view of certain elements composing a gap embodying a preferred form of my invention, together with associated load and discharge circuits; Figs. 2 and 3 are similar views of modifications of the apparatus shown in Fig. 1; Fig. 4 is a side view, partially diagrammatic, of a commercial form of apparatus operative in accordance with the system of Fig. 2; Fig. 5 is a similar view of another form of commercial apparatus embodying my invention; and Figs. 6, 7, 8 and 9 are diagrammatic views of still other forms of apparatus.

In the construction and application of discharge gaps for the protection of transmission lines and similar uses, it is desirable that the gap shall not break down at line potential and the normal frequency but that the gap shall break down at as low a voltage as possible upon the occurrence of abnormal frequencies, such as switching surges and lightning discharges.

In my former application, Serial No. 216,088, filed Feb. 8, 1918, and assigned to the Westinghouse Electric & Manufacturing Company, I disclose apparatus functioning in this manner, an antenna being disposed between the main discharge electrodes and being connected thereto through impedance devices of dissimilar character, the adjustment being such that, at normal frequency, the drops in said impedance devices determine the potential of this antenna at a value substantially the same as that of the immediately adjacent electrostatic field. Upon a

change in the frequency of the system, the drops in the two impedance devices change their relative ratio so as to cause the antenna to assume a potential different from that which the main electrodes strive to set up in the field immediately adjacent to the antenna. Thus, the antenna disturbs the electrostatic conditions with a change in the frequency and this effect may be caused to be so pronounced as to cause a given gap to break down with a high-frequency voltage far lower than the gap will hold at normal frequency.

The present invention is similar to the above in its normal aspects but differs therefrom in detail. Two main electrodes are employed that have a somewhat distorted and non-uniform electrostatic field therebetween and which have, preferably, an impulse ratio of substantial unity. For this purpose, two spheres may be used having a space therebetween considerably exceeding the radius thereof.

One or more conducting members are so disposed and connected to the circuit that, at normal frequency, they serve to largely eradicate the field distortion and concentrations of electrostatic flux, so that the gap is enabled to withstand a relatively high voltage difference at normal frequency. The energizing circuit of the conducting members is so arranged that, upon the occurrence of high frequency, the corrective effect thereof upon the electrostatic field is partially or wholly eliminated, so that currents of abnormal frequency flow freely across the gap, even if of less than normal line voltage.

Referring to the drawing for a more detailed understanding of my invention, I show a main discharge gap at 3, being formed by discharge electrodes 4 and 5, preferably of spherical contour and spaced apart more than their respective radii. The electrode 4 may be connected to a line wire 6, and the electrode 5 may be connected to ground at 7 or the discharge gap may be associated with an electrolytic arrester or be otherwise employed, as is well known to those skilled in the art.

A toroidal shaped conducting member 8 is disposed around the electrode 4 and connected thereto through an impedance device 9 embodying either resistance, reactance, or both. Similarly, a toroidal shaped con-

ducting member 10 surrounds the electrode 5 and is connected thereto through an impedance device 11. A capacitance device 12 may be connected between the members 8 and 10, if desired.

Having thus described the structure of a device embodying my invention, the operation thereof is as follows. Under normal conditions, the adjustment is such that the electrostatic field between the members 4 and 5 would be quite badly distorted, in the absence of the members 8 and 10, and the gap length is such that the gap would be liable to break down at line potential or less. At normal frequency, the device 12 is of extremely high impedance and the devices 9 and 11 serve to maintain the members 8 and 10 at substantially the potentials of the associated electrodes. Under these conditions, the corrective effect of the members 8 and 10 upon the field between the electrodes 4 and 5 is such as to substantially remove the loci of steep potential gradient therefrom, minimizing the liability to breakdown and largely increasing the ability of the gap to withstand potential. Under these conditions, the gap is given a setting far less than would be permissible in the absence of the members 8 and 10. Upon the occurrence of abnormal frequency, the impedance of the devices 9 and 11 remains constant if these members are purely ohmic resistance and largely increases if these members embody reactance while the impedance of the device 12 decreases. Thus, the potential-determining function of the members 9 and 11 upon the members 8 and 10 decreases, permitting the members 8 and 10 to move away from the potential of their immediately associated electrodes. At the same time, the relatively low impedance of the device 12 causes the members 8 and 10 to approach each other in potential, tending to assume a potential intermediate between those of the discharge electrodes. Under these conditions, the corrective effect of the members 8 and 10 upon the electrostatic field is largely reduced, permitting the gap between the electrodes 4 and 5 to break down at a potential difference materially lower than that which was previously withstood at normal frequency.

With certain designs, the inherent capacitance between the members 8 and 10 may be sufficient to perform the function of the condenser 12 and this element may therefore be omitted.

In the construction of a gap embodying my invention, it is unnecessary to employ two potential-adjusting members. Thus, in the gap shown in Fig. 2, the discharge electrodes 4 and 5 are connected between line and ground and a single field-controlling member 8 is associated with the electrode 4, being connected thereto through an

impedance device 9 and being connected to ground through a condensive reactor 12.

The operation of the structure thus shown will be obvious from a consideration of the discussion of Fig. 1.

Referring to the form of my invention shown in Fig. 3, the discharge electrodes and guard rings are as before, as are also the connecting devices 9 and 11.

The guard ring 8 is connected to the discharge electrode 5, however, through a condenser 13 and, similarly, the guard ring 10 is connected to the discharge electrode 4 through a condenser 14. The devices 9 and 11 may embody either pure ohmic resistance or resistance and inductance, as desired and as dictated by the particular design considerations.

In operation, at normal frequency, the impedance of the condensers 13 and 14 is so high that the guard rings 8 and 10 are charged to substantially the potential of their immediately adjacent discharge electrodes, as previously set forth, thus exerting the desired corrective effect on the distorted electric field tending to be established by the electrodes 4 and 5.

Upon the occurrence of an abnormal rise in frequency, the impedance of the members 9 and 11 remains constant, if these members are purely ohmic resistance, and rises if these members embody reactance. At the same time, the reactance of the condensers 13 and 14 decreases to a marked extent so that the guard ring 8 approaches the potential of the electrode 5 and the guard ring 10 approaches the potential of the electrode 4. Thus, the conditions are such that the guard rings 8 and 10 now promote distortion of the electrostatic field, rather than correct the same, and a quick and effective breakdown is secured.

Referring to Fig. 4, a discharge electrode 4 is disposed opposite the electrode 5 in such manner as to normally tend to produce a badly distorted field. The electrode 5 is connected to ground, as through an electrolytic lightning arrester 15. The guard ring 8 surrounds the electrode 4 and is connected thereto through an impedance device 9, as previously described. The guard ring 8 is mounted on an insulator 16 having a grounded metallic pin 17.

Under these conditions, the insulator 16 performs the function of the condenser 12 in the device of Fig. 2, and the electrolytic arrester 15 tends to suppress the free discharge of line energy across the gap after the abnormal frequency disturbance has been removed.

In the apparatus shown in Fig. 5, an electrode 4 is disposed opposite an electrode 5, as before, the latter electrode being grounded through an electrolytic arrester 15. A guard ring 8 surrounds the electrode 4, as in the

device of Fig. 4. The ring 8 carries a horn 18, and the electrode 5 carries an opposing horn 19.

The electrode 4 is carried by a shank 20 supported from an insulator 21 and a charging resistor, shown as of the stick type, is shown at 22. An inductive connection 23 joins the resistor 22 with the guard ring 8.

In the operation of the device thus shown, 10 the member 22 serves as a charging resistor for charging the arrester 15, the gap between the horns 18 and 19 being temporarily bridged by any suitable apparatus. Disturbances of normal frequency but of high 15 voltage take place between the guard ring 8 and the member 5 and are extinguished by the joint action of the arrester 15, of the resistor 22 and of the horn gap 18-19.

Disturbances of abnormal frequency so 20 disturb the potential of the guard ring 8, because of the inductance of the member 23 and the capacitance of the member 16, that a discharge is initiated between the electrodes 4 and 5.

25 With the various forms of apparatus discussed to this point, the guard ring is, at times, of appreciably different potential than its associated discharge electrode, the potential difference with abnormal frequency possibly rising to as great a value as the potential across the gap itself. This necessitates disposing the guard ring at such distance from the discharge electrode as to materially reduce its field-controlling function.

30 Referring to the form of apparatus shown in Fig. 6, means are shown for materially correcting this effect. A discharge electrode 4 is disposed opposite the ground electrode 5, and a guard ring 8 surrounds the electrode 4, as before. An impedance member 25, either inductive or noninductive, is connected between the lead to the electrode 4 and ground through a condenser 26. An intermediate point in the element 25 is connected to the guard ring 8.

35 Under these conditions, the impedance of the device 26 is very high, at normal frequency, and that of the device 25 is relatively low, so that the guard ring 8 approximates the electrode 4 in potential. Upon the occurrence of a discharge of abnormal frequency, the impedance of the device 26 is relatively small, whereas that of the device 25 becomes relatively large, the device 25, 40 in effect, being connected between line and ground. Under these conditions, the potential of the guard ring 8 is intermediate between that of the line and that of ground, the particular value being determined by the 45 point of attachment of the guard ring to the element 25.

In the form of apparatus shown in Fig. 7, 50 guard rings 28 and 29 are associated with the discharge electrode 4 and this electrode 55 is connected to ground through impedance

devices 30, 31 and 32. The devices 30 and 31 may embody pure resistance or resistance and inductive reactance, whereas the device 32 embodies condensive reactance.

At normal frequencies, both of the guard 50 rings are at substantially the potential of the discharge electrode and exert a pronounced field-correcting effect. Upon the occurrence of abnormal frequency, the guard ring 29 assumes substantially ground potential but, by reason of its large size, and consequent spacing from the electrode 4, this does not lead to undesirable discharges. The intermediate guard ring 28, by reason of its closer spacing from the electrode 4, is in greater danger of discharge therefrom but the potential of this guard ring, during abnormal frequency, is fixed by attachment 55 between the elements 30 and 31 as is the potential of the guard ring 8 in Fig. 6.

Another form of apparatus for protecting the guard ring from undesired discharges is shown in Fig. 8. The discharge electrode 4 is connected to ground through condensers 33 and 34, and the condenser 33 is shunted by an impedance device 35, embodying either pure resistance or resistance and inductive reactance. At normal frequency, the condensers 33 and 34 perform little or no action and the potential of the ring 8 is substantially that of the electrode 4 because of the connection through the impedance device 35. With abnormally high frequency, the element 35 may be disregarded and the potential of the guard ring 8 is determined 60 by the relative magnitudes of the condensers 33 and 34, the guard ring being connected therebetween.

Still another form of my invention is shown in Fig. 9 in which the ring 8 is connected to the discharge members 4 and 5 by means of condensers 36 and 37, respectively, which serve to maintain the ring 8 at the desired potential with respect to the electrodes 4 and 5 during normal conditions 65 but which are of insufficient capacity to carry a discharge current. The ring 8 is also connected to the discharge member 4 through an auxiliary spark gap 38, which, being of a high impulse ratio, will break 70 down at a slight over-voltage of normal frequency, bringing said ring to substantially the potential of the electrode 4 and preventing a main gap discharge until a considerably higher voltage has been reached. On 75 the other hand, a high-frequency over voltage will discharge across the main gap before breaking down the auxiliary gap and at a lower voltage than a normal-frequency over voltage, on account of their respective 80 impulse ratios.

Throughout this specification, I have disclosed guard members of toroidal shape, as, under most operating conditions, this is the most effective form of device but, obviously, 85

- 21 a partial toroid or guard ring or member of many other shapes would function in a similar manner, although, generally speaking, to a lesser degree.
- 5 Furthermore, in many relations where I have shown a condenser, the inherent condensance between adjacent conducting elements is sufficient to perform the desired function and, thus, in many cases, the condensers shown may be considered as merely illustrative and may be omitted in the actual construction of the device.
- 10 It will be noted that the device of Fig. 3 causes the development of a greater voltage between guard ring and the associate electrode under high-frequency conditions than does the structure of Fig. 1, whereas, the device of Figs. 6, 7 and 8 provides for the establishment of lesser voltages than are developed in the system of Fig. 1 under similar conditions. The particular design to be followed depends largely upon design considerations, such, for example, as operating voltage and the radii of the curvature of the electrodes 4 and 5 and of the respective guard rings. I show these different forms of structure so as to illustrate the wide flexibility of design that is possible under the fundamental principles herein set forth and to emphasize the wide adaptability of the present structure in the protection of transmission lines from undesired high-frequency impulses.
- 15 While I have shown my invention in a plurality of forms, it will be obvious to those skilled in the art that it is not so limited but is susceptible of various minor changes and modifications without departing from the spirit thereof and I desire, therefore, that only such limitations shall be placed thereupon as are imposed by the prior art or are specifically set forth in the appended claims.
- 20 I claim as my invention:
- 45 1. In electrical-discharge-gap apparatus, the combination with two discharge members mounted in spaced relation to each other, of means surrounding one of said discharge members but spaced therefrom and adapted to prevent distortion of the electrostatic field between said discharge members at normal frequency of said circuit and to permit the distortion thereof at other than normal frequency.
- 55 2. In electrical-discharge-gap apparatus, the combination with two discharge members mounted in spaced relation to each other, of an auxiliary electrode surrounding one of said discharge members but spaced therefrom, and connections embodying impedance members of dissimilar character between said auxiliary electrode and said discharge members, respectively, said connections having impedances, at the normal frequency of said circuit, substantially proportional to the distance between said auxiliary electrode and said discharge members, respectively.
3. In electrical-discharge-gap apparatus, the combination with two discharge members mounted in spaced relation to each other, of an auxiliary electrode mounted adjacent each of said discharge members and connected thereto and to each other by means of connections having impedances of dissimilar impedance character.
4. In an electrical-discharge-gap apparatus, the combination with two discharge members mounted in spaced relation to each other, of an auxiliary toroidal shaped electrode mounted to surround one of said discharge members in spaced relation, and connections between said auxiliary electrode and said discharge members, one of which embodies non-capacitative impedance and the other of which embodies capacitance.
5. In electrical-discharge-gap apparatus, the combination with two discharge members mounted in spaced relation to each other, of auxiliary electrodes mounted adjacent each of said discharge members, connections between each of said auxiliary electrodes and the adjacent discharge member embodying impedance, and a connection between said auxiliary electrodes embodying impedance of a nature dissimilar to that previously mentioned.
6. In electrical-discharge-gap apparatus, the combination with two discharge members mounted in spaced relation to each other, of auxiliary electrodes mounted adjacent each of said discharge members, connections between each of said auxiliary electrodes and the adjacent discharge member embodying non-capacitative impedance, and a connection between said auxiliary electrodes embodying capacitance.
7. In electrical-discharge-gap apparatus, the combination with two discharge members mounted in spaced relation to each other, of auxiliary toroidal electrodes mounted to surround each of said discharge members, connections between each of said auxiliary electrodes and the adjacent discharge member embodying non-capacitative impedance, and a connection between said auxiliary electrodes embodying capacitance.
8. In electrical-discharge-gap apparatus, the combination with two discharge members mounted in spaced relation to each other, of auxiliary toroidal electrodes mounted to surround each of said discharge members, connections between each of said auxiliary electrodes and the adjacent discharge member embodying resistance and reactance, and a connection between said auxiliary electrodes embodying capacitance.
9. In electrical-discharge-gap apparatus, the combination with two discharge members mounted in spaced relation to each other, of auxiliary electrodes mounted to surround each of said discharge members, connections between each of said auxiliary electrodes and the adjacent discharge member embodying resistance and reactance, and a connection between said auxiliary electrodes embodying capacitance.

other, of auxiliary toroidal electrodes mounted to surround each of said discharge members, and connections between each of said auxiliary electrodes and the adjacent discharge member embodying non-capacitive impedance.

10. In electrical-discharge-gap apparatus, the combination with two discharge members mounted in spaced relation to each other, of auxiliary toroidal electrodes mounted to surround each of said discharge members, connections between each of said auxiliary electrodes and the adjacent discharge member and between the two auxiliary electrodes embodying impedances, said impedances being of such value that the auxiliary electrodes are maintained at substantially the potential of the discharge member they surround at normal frequency 20 of the supply circuit, and are charged at a potential different from that of the discharge member they surround at other frequencies of the supply circuit.

11. In electrical-discharge-gap apparatus, the combination with two discharge members mounted in spaced relation to each other, of auxiliary toroidal electrodes mounted to surround each of said discharge members, connections between each of said auxiliary electrodes and the adjacent discharge member and between the two auxiliary electrodes embodying impedances, said impedances being of such value that the auxiliary electrodes are maintained at substantially the potential of the discharge members they surround at normal frequency of the supply circuit, and are of substantially equal potential at relatively greater frequencies of the supply circuit.

40 12. The combination with a discharge device provided with a gap and having discharge members so arranged as to tend to produce a distorted electrostatic field therebetween, of a conducting member disposed adjacent said device and connected to one of said discharge members through impedance means that change in effective impedance with changes in the frequency impressed upon said device, whereby the modifying action of said conducting member upon the electrostatic field of said gap changes with changes in said frequency.

13. The combination with a discharge device provided with a gap and having discharge members so arranged as to tend to produce a distorted electrostatic field therebetween, of a conducting member disposed adjacent said device and connected to the circuit thereof through impedance means 55 that change in effective impedance with changes in the frequency impressed upon said device, whereby the modifying action of said conducting member upon the electrostatic field of said gap changes with changes in said frequency, said connecting means and

the disposition of said conducting member being such that, at a predetermined frequency, said field distortion is substantially eliminated.

14. The combination with a source of alternating current, of means providing a discharge gap connected thereto and embodying discharge electrodes so arranged as to tend to produce a distorted electrostatic field therebetween, an antenna member so disposed with relation to said gap as to substantially correct said field distortion if energized to a predetermined potential, and connecting means embodying reactance between said antenna member and the circuit 70 of said gap providing means, said reactance being such that, at normal frequency of said source, said antenna member is properly charged for the correction of said field and, at other frequencies, said antenna member is 75 improperly charged to produce this effect.

15. In a discharge-gap apparatus, the combination with means providing a gap having a distorted field, of means for correcting said distortion at a predetermined 90 frequency, said corrective means being substantially ineffective at materially different frequencies.

16. The method of operating a discharge gap to discharge potentials of other than a 95 desired frequency and to prevent the discharge of potentials of said frequency which comprises tending to maintain a distorted field in said gap, eliminating said distortion at said desired frequency and permitting 100 said distortion at other frequencies.

17. In electrical-discharge-gap apparatus, the combination with two discharge members mounted in spaced relation to each other, of means for preventing distortion 105 of the electrostatic field between said discharge members at normal frequency of said circuit and to permit the distortion thereof at other than normal frequency.

18. In combination, a discharge gap comprising two spaced electrodes, and a substantially ring-shape member surrounding one of said electrodes, and an electrical connection between said member and the electrode which it surrounds comprising impedance.

19. In combination, a discharge gap comprising two spaced electrodes, and a substantially ring-shape member composed of electrical-current-conducting material 120 surrounding each of said electrodes and spaced therefrom.

20. In combination, a discharge gap comprising two spaced electrodes, and a substantially ring-shape member composed of 125 electrical-current-conducting material surrounding each of said electrodes, each of said ring-shape members being electrically connected to the electrode which it surrounds but spaced therefrom.

21. In combination, a discharge gap comprising two spaced electrodes, and a substantially ring-shape member composed of electrical current conducting material surrounding each of said electrodes, each of said ring-shape members being electrically connected to the electrode which it surrounds, said ring-shape members being connected together electrically.
- In testimony whereof, I have hereunto¹⁰ subscribed my name this 24th day of March, 1919.

CHESTER T. ALLCUTT.
